CYLINDER CONSTRUCTION FOR INTERNAL COMBUSTION ENGINES

Adolf Houmoller, Charlottenlund, near Copenhagen, Denmark

Application February 10, 1939, Serial No. 255,744
In Denmark December 17, 1938

6 Claims. (CL. 123—173)

Diesel engines are known having the cylinder bipartite in such a manner that the two cylinder liners produced by the division rest direct one on the other, being held together by the pressure of long stay bolts. This design suffers from the drawback that the elongation of the topmost portion of the cylinder liner arising from the heat expansion must be taken up by the stay bolts, this necessitating a suitable long length or a special construction of the latter. By the construction described furthermore the influence on the cylinder cover is increased.

This present invention relates to a multipartite, especially bipartite cylinder construction, which according to the invention is built in that special manner that the upper cylinder liner is freely suspended, that is suspended at or in the vicinity of its topmost end, so that it may expand freely in a downwardly direction. It is hereby obtained that the assembly bolts of the machine need not take up any strain deriving from the heat expansion of the said portion of the cylinder liner.

It is per se known to build engines having a freely suspended cylinder liner, but the latter is not, in such case multipartite, and will therefore have free heat expansion in a downwardly direction. This present invention purports especially to ensure for the topmost portion of a bipartite cylinder liner a similar freedom for expansion in a downwardly direction, but the principle of the invention may be adapted also to cylinder liners divided into three or more parts disposed one above the other. The multipartite cylinder liner is in such case arranged in such a manner that not only the uppermost portion is suspended at the top and ensured free heat expansion downwardly, but the liner parts lying further downwardly are mounted in a similar manner in that each of the two or more cylinder liners constituting the cylinder are suspended separately in different parts of the machine's frame construction, and in such a manner that all the liner parts may expand freely in a downwardly direction during the heat expansion.

The cylinder construction is in practice preferably built so that the cylinder liner is divided into two parts and in such a manner that the lower cylinder liner will be suspended in the machine's relatively low frames, or in a scavenging air belt carried by the frames. This scavenging air belt generally takes the form of a horizontal through girder in the machine. The upper cylinder liner is suspended by its flange in

the cover, which in turn is suspended by an upper flange affixed to a cylinder frame resting on the frames, or on the scavenging air belt resting on the frames. It is hereby obtained that the cylinder frame may be assembled with the scavenging air belt, or possibly direct with the lower frame by means of relatively short bolts, so that the upper cylinder liner may be removed separately, the lower liner remaining in the machine and forming a guide for the piston. The piston may, when the top portion of the machine and the upper liner have been removed, be inspected, repaired or if so desired removed in an easy manner. The said relatively short assembly bolts need not take up any strain deriving from the heat expansion of the upper cylinder liner or from the cylinder as such, but will only have to take up the gas pressure.

In order to ensure the correct relative positions of the two cylinder liners, the lower portion or bottom edge of the upper cylinder liner is normally guided in a recess in the top of the lower liner, the recess having so much clearance that the upper liner will never rest on the lower liner; hence the heat expansion will not be obstructed. A similar guiding may also be used if the cylinder is divided up into more than two parts.

With the above and other objects in view, the invention is shown in the drawing in which:

30 Figure 1 shows a central vertical sectional view through a cylinder with certain parts in elevation.

Figure 2 is a sectional view taken upon the section line II—II of Figure 1.

35 In the constructional form for the invention as shown on the drawing the cylinder is bipartite. The upper cylinder liner 1 is by means of the flange 2 suspended in a cover 3 with a suitable outwardly projecting flange 8, and by assembly bolts not shown. The cover 3 has an outwardly projecting flange 9 at the top, and is by means of bolts (not shown) screwed on to an inwardly projecting upper flange 10 on a cylinder frame 4, which at the bottom rests on a scavenging air belt 5. From a blower scavenging air is admitted into the scavenging air belt through a piping 17 which may be common to several cylinders. The air enters the scavenging air belt through an opening 18. The scavenging air belt 5 forms generally a horizontal, longitudinally extending girder in the machine, and is carried by the frames 7 which form the bottom part of the machine's frame construction, or which may possibly at the bottom rest on a bed frame. The parts 5 and 7 are assembled by means of stay

bolts 15. The cylinder frame 4 is, as shown by the drawing, assembled with the scavenging air belt 5 by means of comparatively short assembly bolts 11. When the bolts' tightening nuts 12 are removed, the piston—which, for the sake of distinctness, is not shown on the drawing—may, following the removal of the top portion of the machine and the upper cylinder liner 1, be inspected in an easy manner, and for instance fitted with new rings, the lower liner 6 remaining in the machine and forming a guide for the piston.

The lower liner 6 in which are the scavenging air ports 19 is at its top end suspended in a scavenging air belt 5, for instance as shown on the drawing, resting with a flange 13 on an inwardly directed flange 16 at the top of the scavenging air belt.

In order to ensure the mutual guiding of the two cylinders liners 1 and 6, and at the same time provide space for the heat expansion of the upper liner 1, the lower portion or edge of the latter is guided in a recess 14 in the top portion of the lower cylinder liner 6. The recess 14 is of such depth that the upper liner 1 may expand freely due to heat, without treading on the bottom of the recess. If desired an outward projection may be provided on the outer side of the lower portion of the liner 1, so that a suitable resilient packing may be inserted between the said projection and the flange 13 on the lower liner 6.

The cylinder construction as a whole is built so as to ensure that both the upper and the lower cylinder liners may have free heat expansion in a downwardly direction, and it will be seen from the drawing further, that the lower cylinder liner 6 may be constructed with a removable skirting.

The invention is not confined to a bipartite cylinder construction, seeing that the cylinder liner may be divided into more than two parts, each of which are arranged so as to be suspended separately at or in the vicinity of the top end, and each being carried separately by the machine's outer frame construction, and in such a manner that the parts constituting the cylinder lining will all have free heat expansion in a downwardly direction.

If so desired, the upper cylinder liner 1 may, instead of being suspended in the cover 3 as shown in the drawing, be suspended in such a manner that it rests on the upper side of the cylinder frame 4 with an outwardly projecting flange, in a manner similar to that in which the liner 6 with the flange 13 rests on the upper side of the scavenging air belt 5. If the upper liner is arranged so as to rest on the top edge of the cylinder frame 4 with an outwardly projecting flange, then the cylinder frame 4 must be shaped in such a manner that the cover can be affixed at the top of the cylinder frame. This may possibly be effected by using only one series of assembly bolts, which at the same time ensure tightness between the cover and the upper cylinder liner, serving further to secure the cover to the cylinder frame.

I claim:

1. A cylinder construction for single-acting internal combustion engines comprising an outer frame construction and a cylinder liner, said liner being divided into upper and lower parts, the upper liner part being carried at its top in the outer frame construction of the engine and

having free heat expansion downwardly, and the lower liner part placed below the said upper liner part being likewise carried at its top in the outer frame construction of the engine and having free heat expansion downwardly.

2. A cylinder construction for single-acting internal combustion engines comprising an outer frame construction and a cylinder liner and a cover, said liner being divided into upper and lower parts, and upper liner part being carried at its top in the outer frame construction of the engine, preferably by means of the cover, and having free heat expansion downwardly, and the upper liner part being guided with its lower part in a recess in the top of the lower liner part placed below the said upper liner part, and said recess being so deep that free heat expansion downwardly of the former liner part is secured by means of the recess.

3. A cylinder construction for single-acting internal combustion engines comprising an outer frame construction provided with a scavenging air belt and a cylinder liner, said liner being divided into upper and lower parts, the upper liner part being carried at its top in the outer frame construction of the engine, and having free heat expansion downwardly, and the lower liner part being carried at its top in the scavenging air belt of the frame construction and having free heat expansion downwardly.

4. A cylinder construction for single-acting internal combustion engines comprising an outer frame construction provided with a scavenging air belt a cylinder liner and a cover, said liner being divided into upper and lower parts, the upper liner part being suspended from the cover of the cylinder construction, the said cover being carried by said cylinder frame resting, on said scavenging air belt of the frame construction, the lower liner part being carried at its top in the said scavenging air belt, and having free heat expansion downwardly, and the upper liner part being guided with its lower part in a recess in the top of the lower liner part placed below the said upper liner part, the said recess being so deep that free heat expansion downwardly of the upper liner part is secured by means of the recess.

5. A cylinder construction for single-acting internal combustion engines, comprising an outer frame construction and a cylinder liner, the said liner being divided into an upper liner part and a plurality of lower liner parts, said upper liner part being carried at its top in the outer frame construction of the engine and having free heat expansion downwardly, the liner part placed below the said upper liner part being likewise carried at its top in the outer frame construction of the engine and having free heat expansion downwardly, and the upper liner part being guided with its lower part in a recess in the top of the said lower liner part placed below the said upper liner part, the said recess being so deep that free heat expansion downwardly of the upper liner part is secured by means of the recess.

6. A cylinder construction for single-acting internal combustion engines, comprising an outer frame construction and a cylinder liner, said liner being divided into a plurality of liner parts each part being carried at its respective top by the outer frame construction of the engine and having free heat expansion downwardly.
